UNITED STATES PATENT OFFICE.

ALFRED D. MOSBY, OF CHICAGO, ILLINOIS, ASSIGNOR TO MARSH-CAPRON MANUFACTURING COMPANY, OF CHICAGO, ILLINOIS, A CORPORATION OF ILLINOIS.

APPARATUS FOR DISTRIBUTING CONCRETE.

1,267,440.

Specification of Letters Patent. Patented May 28, 1918.

Application filed March 19, 1915. Serial No. 15,539.

To all whom it may concern:

Be it known that I, ALFRED D. MOSBY, a citizen of the United States, residing at Chicago, in the county of Cook and State 5 of Illinois, have invented certain new and useful Improvements in Apparatus for Distributing Concrete, of which the following is a specification.

My invention relates to apparatus for distributing material such as mixed concrete, for example, and the principal object of the invention is to provide an apparatus suitable for use in connection with a concrete mixer which may be supported, if desired, 10 on the truck or other structure supporting the mixing drum and the other apparatus constituting the concrete mixing machine, and which is adapted to receive batches of mixed concrete from the mixer and to deliver the same at different points, according 15 to the requirement of the particular job. The device of my invention is of particular utility as forming part of a machine for laying concrete pavements or concrete foundations for pavements in streets, alleys, or 20 the like. In this kind of work the concrete has to be distributed over a considerable area. It is not convenient to move the machine itself from place to place for each 25 batch of concrete delivered from the mixer. The customary way is to use hand barrows for making the distribution. This is laborious and expensive.

My invention provides a relatively inexpensive, simple, and compact apparatus for accomplishing the distribution of concrete work of this sort by means of a gravity chute. Concrete mixers are frequently provided with tilting discharge troughs which, 30 in their tilted down position, discharge the mixed concrete out of the drum by gravity. It is not possible to utilize this kind of a device for discharging the concrete to a point at any considerable distance from the 35 mixing drum. In order that mixed concrete should be discharged by gravity through a chute or trough, the inclination of the latter must be considerable—approximately at a slant of one to three. If the ordinary 40 discharge trough is made long enough to reach for any distance from the drum, the slant will not be sufficient to cause a gravity discharge of the material, unless the mixing machine be raised to a very considerable 45 height above the ground. This is not de-

sirable, as it necessitates an additional power and labor in elevating the ingredients of the concrete, and for other reasons which will be apparent.

My invention consists in certain novel arrangements, constructions and devices, to be hereinafter described and claimed, whereby the distribution of the concrete at points remote from the mixer may be accomplished without raising the mixing machine from 60 its normal position above the grade. The invention further consists in certain other novel and improved constructions and devices relating to concrete mixing machines, and particularly means for distributing the 65 concrete after it is mixed, which will be hereinafter more particularly described.

The invention is illustrated in two somewhat different embodiments, both apparatuses, however, operating upon the same 70 general principles.

In the drawings:

Figure 1 shows, in side elevation, one form of the invention;

Fig. 2, a fragmentary side elevation of 80 the distributing chute showing a gate in its open position for discharging the concrete at a point in advance of the end of the chute; and

Fig. 3, a view similar to Fig. 1, illustrating a modified construction.

Like characters of reference designate like parts in the several figures of the drawings.

Referring first to Figs. 1 and 2, 10 designates a mixing drum of the revoluble type, 90 provided with a gear ring 11 meshed by a pinion 12 on a driving shaft 13. The drum and the mechanism for driving the same are shown only fragmentarily. Any suitable form of mixer might be employed. The 95 mixing drum and associated apparatuses are shown as supported on a truck 14. The mixed concrete is discharged from the drum by means of a tilting discharge trough 15, the full lines showing the trough in its discharging position and the dotted lines in its 100 inoperative position.

Pivoted at 16, 17 to the platform of the truck and to a stationary framework 18 thereon is a framework or boom 19 to the 105 outer end of which is pivoted the distributing chute 20, the boom being provided with bearing blocks 21 for a short shaft 22 extending through brackets 23 on the chute. The inner end of the chute is preferably in 110

the form of a hopper 24 between which and the chute proper is a gate 25 carried on a rocking shaft 26 having an operating handle 27. The purpose of the gate is to retain the material in the hopper end of the chute until the time comes to discharge it. The normal or receiving position of the chute is shown in the full lines, Fig. 1. In this position the hopper 24 stands just below the end of the discharge trough 15 in the discharging position of the latter. Mechanism of any suitable sort is provided for tilting the distributing chute 20 to the position shown in the dotted lines in Fig. 1, that is, to its discharging position. For example, the hopper or receiving end of the chute may be provided with a bail 28, attached to which is a cable 29 that extends over sheaves 30, 31 on the boom 19 and over sheaves 32, 33 on the framework 18, and thence to a winding drum 34 adapted to be connected by a clutch 35 to the driving shaft 13 of the mixer.

Operation: When a batch of concrete has been properly mixed, the discharge trough 15 is tilted down from the dotted position to the full line position and the concrete is thereupon discharged into the receiving hopper 24 of the distributing chute 20. Gate 25 is closed ordinarily. The discharge trough 15 is then moved back to its inoperative position and the winding drum 34 clutched to shaft 13. The distributing trough is then raised to its discharging position, the position shown in the dotted lines in Fig. 1. The winding drum is preferably provided with a band-brake device 36 adapted, when the drum 34 is released from shaft 13, to hold the drum from turning. The band-brake has an operating lever 37 which is adapted to release the band so as to allow the distributing chute to descend slowly after it has discharged the batch.

Either before or after the distributing trough has been elevated to its discharging position the boom 19 may be swung on its pivots 16, 17 to such extent as may be necessary to cause the delivery of the batch to the right place on the grade. This may be done by hand or by means of any suitable mechanism.

To discharge the material the gate 25 is raised. The discharge takes place by gravity. Preferably the distributing chute is constructed as shown in my co-pending application, Serial No. 2890 filed January 18, 1915, with one or more gates 38 which may be dropped so as to discharge the material before it reaches the end of the chute.

In Fig. 3 I have shown a modified construction in which the distributing chute designated 20^a is shifted inwardly toward the truck during its tilting movement after it has cleared the end of the discharge trough of the mixer. The distributing chute in this construction is attached to the end of the

boom 19^a by means of links 39. The boom is provided with tracks 40; the upper ends of which are curved. The hopper end 24^a of the distributing chute is provided with pairs of rollers 41 standing on opposite sides of the tracks 40. The curvature of the tracks causes the chute to be shifted inwardly during its tilting movement, the shifting movement commencing after the chute has cleared the end of the up-tilted discharge trough of the mixer. The object of this arrangement is to maintain the center of gravity of the chute and its load as close to the truck as possible, thereby minimizing the tendency to instability.

While I have described my invention in certain preferred embodiments, it will be realized that modifications might be made, other than those suggested, without departure from the principles of the invention. Therefore I do not wish to be understood as limiting the invention to the particular constructions, arrangements, and devices described and shown, except so far as the claims appended hereto are expressly so limited.

I claim:

1. In apparatus of the character described, the combination with the supporting frame, of a boom vertically pivoted to said supporting frame, a distributing chute pivoted near its discharge end to the boom, guide members on the boom, guide engaging members on the chute, and means for hoisting the receiving end of said chute substantially vertically along said guide members.

2. In apparatus of the character described, the combination with the supporting frame, of a boom vertically pivoted to said supporting frame, a distributing chute pivotally secured near its discharge end to the outer end of the boom and provided at its inner end with a receiving hopper, guide members on the boom, guide rollers on the chute, and means for hoisting the receiving end of said chute substantially vertically along said guide members so as to tilt the same to its discharge position.

3. In apparatus of the character described, the combination with a supporting frame, of a boom pivoted on a vertical axis to said supporting frame, a chute pivotally secured to the boom, means for tilting said chute to its discharging position, and a guiding track which at the same time shifts the chute bodily toward said supporting frame.

4. In apparatus of the character described, the combination with a supporting frame, of a distributing chute, a pivoted link on which the outer end of said chute is mounted, means for hoisting the inner end of said chute so as to tilt the same to its discharging position, and means for causing the chute, when raised, to move inwardly toward the supporting frame.

5. In apparatus of the character described, the combination with a supporting frame, of a boom pivoted on a vertical axis to said supporting frame, a chute pivotally secured 5 to the boom, means for tilting said chute to its discharging position, and an automatically operated gate in said chute to retain the material in the receiving end of the chute.

6. In apparatus of the character described, 10 the combination with the supporting frame, of a distributing chute, means providing a shifting pivot for the outer end of said chute, means for hoisting the inner end of said chute so as to tilt the same to its discharging position, and guiding means for causing 15 the chute, when raised, to be moved inwardly toward the supporting frame.

7. In apparatus of the character described, 20 the combination with a supporting frame, of a distributing chute, means providing a shifting pivot for the outer end of said chute, means for hoisting the inner end of said chute so as to tilt the same to its discharging position, a curved guiding track, 25 and rollers on said chute which engage said track for the purpose described.

8. In apparatus of the character described, the combination with a supporting frame, 30 of a distributing chute, means providing a shifting pivot for the outer end of said chute, means for hoisting the inner end of said chute so as to tilt the same to its discharging position, a curved guiding track, 35 rollers on said chute which engage said track to shift the chute bodily on the supporting

frame, a gate to retain the material in said hopper, and a cam on said track adapted to automatically operate said gate.

9. In apparatus of the character described, 40 the combination with a source of supply for the material to be distributed, of a distributing chute provided at its inner end with a receiving hopper, the rear edge of which, when in position to receive material, is overhung by the discharge spout of said source of supply, means providing a shifting pivot for the outer end of said chute, 45 means for tilting said chute, and means for causing the chute to shift outwardly from said source of supply so as to clear said discharge spout and then shift inwardly after 50 the spout is cleared while the said chute is being tilted.

10. The combination with a receptacle for material, of a spout, means to deliver material from said receptacle to said spout, a frame supporting the said spout, mounted upon vertical pivots so as to be free to swing upon them, the frame being provided with guideways that direct the up and down 55 movements of the inner end of the spout, a cable connected with the inner end of the spout, winding means for the cable, and manually controlled power actuated devices through which said cable is wound up and 60 let off.
